Filed Jan. 26, 1967, Ser. No. 5,575

Term of patent 14 years

(Cl. D29—23)

FIG. 4.

FIG. 5.

FIG. 7.

FIG. 6.

FIG. 1 is a front perspective view of a combined votive altar and coin depository showing my new design.

FIG. 2 is a front elevation thereof, the broken line showing of the figurines in this view being merely for illustrative purpose.

FIG. 3 is a vertical section taken along line 3—3 of FIG. 2.

FIG. 4 is an elevational view of the lefthand side of FIG. 2.

FIG. 5 is an elevational view of the righthand side of FIG. 2.

FIG. 6 is a top plan view of FIG. 2.

FIG. 7 is an elevational view of the back side of the same as seen from the lefthand side of FIG. 4.

The essential features of the design reside in the portions shown in solid lines.

I claim:

The ornamental design for a combined votive altar and coin depository, as shown and described.
